(57) **CLAIM**

The ornamental design for a baby bottle warmer, as shown and described.

DESCRIPTION

FIG. 1 is a rear and bottom perspective view of a baby bottle warmer design in a closed state, showing our new design. FIG. 2 is a front and top perspective view of a baby bottle warmer.

FIG. 3 is a front view of a baby bottle warmer.

FIG. 4 is a rear view of a baby bottle warmer.

FIG. 5 is a left side view of a baby bottle warmer.

FIG. 6 is a right side view of a baby bottle warmer.

FIG. 7 is a top view of a baby bottle warmer.

FIG. 8 is a bottom view of a baby bottle warmer; and, FIG. 9 is an enlarged view of a baby bottle warmer taken from the circle part in FIG. 7.

Any shading and cross-hatching are not features of the design but are utilized to illustrate the surface contours of the baby bottle warmer design in the drawings.
